Primary Examiner — Terry Wallace(74) Attorney, Agent, or Firm — Robert C. Montgomery;
Montgomery Patent & Design, LP(57) CLAIM

The ornamental design for an under cabinet-mounted spice rack, as shown and described.

DESCRIPTION

FIG. 1 is a perspective front view of an under cabinet-mounted spice rack, showing my new design;

FIG. 2 is a front side view thereof;

FIG. 3 is a back side view thereof;

FIG. 4 is a right side view with the left side view being a mirror image thereof;

FIG. 5 is a top side view thereof; and,

FIG. 6 is a bottom side view thereof.

The broken lines are for illustrative purposes only and form no part of the claimed design.
